[57] CLAIM

The ornamental design for a robotic figure, as shown and described.

DESCRIPTION

FIG. 1 is a front perspective view of a robotic figure embodying our new design, showing the figure's arms in an open position;

FIG. 2 is a right side perspective view of the figure, showing the figure's arms in a closed position;

FIG. 3 is a rear perspective view of the figure; and,

FIG. 4 is a top plan view of the figure.

FIG. 1.

FIG. 2.

FIG. 3.

fig. 4.
